UNITED STATES PATENT OFFICE

SYLVARIUS A. SPRINKLE, OF MARTINSBURG, WEST VIRGINIA

RAIL JOINT

Application filed June 1, 1931. Serial No. 541,452.

My present invention has reference to a rail joint and has for its primary object to simplify, improve and cheapen the rail joint construction upon which I, on Feb. 14, 1931, applied for U. S. Letters Patent, the application bearing Serial No. 515,888.

To the attainment of the foregoing the invention consists in the improvement hereinafter described and definitely claimed.

10 In the drawings:

Figure 1 is a side elevation of two railway rails connected in accordance with this invention.

15 Figure 2 is a horizontal sectional view approximately on the line 2—2 of Figure 1.

Figure 3 is a transverse sectional view approximately on the line 3—3 of Figure 1.

As is true with respect to my application Serial No. 515,888, my present joint is arranged between two of the ties 1, upon which are spiked rails 2 that have their confronting ends disposed approximately centrally with respect to the distance between the ties 1. The improvement contemplates the employment of two rail chairs which are of a similar construction and each of which is broadly indicated by the numeral 3. Each chair 3 has a base 4 from adjacent whose inner edge there arises a vertical flange 5 and each of the flanges is integrally formed with an outstanding horizontal wall 6 of a materially greater thickness than the flange 5 and the base 4. The base flanges of the rails 2 are designed to rest on the upper face of the walls 6, and the outer edges provided by the walls are formed with vertical extensions 7 which have angularly arranged flanges 8 that overlie the walls 6 and contact with the upper faces of the base flanges of the rails 2. The outer faces provided by the walls 6 and the extensions 7 are straight, but the outer corners of the extensions 7 are inclined inwardly, as at 10, and merge into flanges 11 which underlie and afford rests for the heads of the rails 2. Below the flanges 11 the extensions 7 are grooved or concaved longitudinally, as at 12, and the walls provided by these grooves are rounded.

50 The webs of the rails 2, adjacent to their confronting ends are provided with bolt

openings 13 and through these openings there are freely passed the offset ends 14 of a tie bolt 15. The tie bolt is received in one of the pockets provided by one of the grooves 12 and the angle ends or arms 14 thereof are 55 of such length as to prevent their passage entirely through the openings 13, as the body of the bolt is arranged in close proximity to the wall of the groove or pocket in which it is received. The tie bolt 15 is an important 60 element of the improvement inasmuch as the same limits the movement of the rails in the expansion and contraction thereof and likewise permits of one of the rails expanding and contracting to a greater extent than the 65 other rail.

The chair members 3 are received in a body which is made up of a pair of angle members to include a comparatively thick base 16 and a side 17. The base 16 of the body members, 70 at the confronting ends thereof, is cut angularly to form the same with longitudinally extending grooves and with hooks 18, respectively to be received in the grooves. This establishes an interlocking engagement between the body sections. At points adjacent to the ends of the joint I pass through the yieldable sides 17 of the body and through the horizontal portion of the chair which I have termed the walls 6, bolt members 19 engaged 75 by suitable nuts 20. By tightening the nuts the upper portions of the chair members are forced together so that a proper frictional engagement between the chair members and the rail may be at all times attained. By reference to the drawings it will be noted that the joint projects below the rails a distance approximately equaling the height of the ties 1 and the roadbed is packed under the joint to sustain the same at a proper elevation. 80 The packing thus prevents the sinking of the joint which is materially assisted by the rails connected by the joint. 90

It is believed the foregoing description, 95 when read in connection with the drawings, will fully and clearly set forth my construction and the advantages thereof so that further detailed description will not be required, but obviously I do not wish to be restricted to the precise details herein set forth and, 100

therefore, hold myself entitled to make such changes therefrom as fairly fall within the scope of what I claim.

Having described the invention, I claim:

- 5 1. A rail joint comprising two members of a length to be received between two supporting ties for rails and of a height to rest upon the roadbed, said members receiving and wedging therebetween the confronting ends of two rails and said members being provided with pockets, a tie bolt having angle ends, said tie bolt being received in one of said pockets and the ends thereof passing through the webs at the confronting ends of the rails,
- 10 15 a two-part housing for the rail supporting and wedging members and means passing through the housing and the members for forcing the members toward each other and for sustaining the housing on the members.
- 15 20 2. A rail joint comprising two members to rest on the roadbed between two of the supporting ties for the rails, said members having their sides channeled from adjacent the base thereof to afford upper rail supporting walls, overlying angle flanges arranged above the walls to contact with the outer base flanges of the rails when received on said rails, and having upper angle portions to underlie and afford rests for the heads of
- 25 30 35 rails, pockets below said flanges, one of said pockets designed to receive therein a tie bolt having angle ends to be freely received through bolt openings in the webs of supporting rails, a two-part housing for the rail supporting members and adjustable means passing through the sides of the housing and the rail supporting walls of the members for holding the housing on the members and for compressing the members toward each other.
- 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910

In testimony whereof I affix my signature.
